UNITED STATES PATENT OFFICE.

ALFRED GUSTAFSON, OF AURORA, ILLINOIS, ASSIGNOR, BY MESNE ASSIGNMENTS, TO THE WELCH MANUFACTURING COMPANY, A CORPORATION OF MICHIGAN.

DISPLAY-FIXTURE FOR GARMENTS.

1,138,601.

Specification of Letters Patent.

Patented May 4, 1915.

Application filed March 22, 1911. Serial No. 616,106.

To all whom it may concern:

Be it known that I, ALFRED GUSTAFSON, citizen of the United States, residing at Aurora, in the county of Kane and State of Illinois, have invented certain new and useful Improvements in Display-Fixtures for Garments, of which the following is a specification.

My invention relates to display fixtures for use in show cases or cabinets, and designed to support garments or similar articles, and the chief objects of the improvements which constitute the subject matter of this application for patent are:—to provide a fixture that will be available to support various articles of wearing apparel in a manner to properly exhibit them for inspection; to arrange a simple and easily operated mechanism to adapt the apparatus to be shifted or revolved so as to assume a variety to facilitate the convenient and complete inspection of the garments supported thereon. These main objects, and others of importance, are accomplished by employing the apparatus illustrated in the accompanying drawing, which forms a part of this application.

The details of construction and manner of assembling are disclosed in the several views which, briefly described, are as follows:—

Figure 1 is a sectional elevation, the cutting plane being transversely to the carriage track; Fig. 2 is a top plan view of the guide plate; Fig. 3 is a longitudinal sectional view of the base and a portion of the column.

Referring to the details of the drawings, the numeral 5 indicates a vertical pillar or column, comprising a central post or shaft 6 of suitable length and having its lower end reduced and provided with threads 7 which engage a threaded boss in an upper rectangular bearing plate 8, which has two opposite margins supported on parallel rails 9, connected at the ends by tie pieces 10 and supported above the floor 11 by frame pieces 12, which have legs 13 secured to the main floor 11 by bolts or spikes 14. Beneath the track is arranged a lower bearing plate 15 of the same size as the upper plate 8, and adjustably secured thereto by bolts 16. The opposite margins of this plate engage the under sides of the track as in the case of the plate 8. The plates 8 and 15 secured together in the manner described constitute a carriage which is adapted to travel on the

track formed by the rails 9, and to reduce friction I introduce balls 17 between the bearing parts, the contacting surfaces being provided with suitable retaining grooves or channels 18 in which the balls roll. Ball retaining plates 17^a are provided to secure proper spacing of the balls 17, so that the carriage will be properly supported at every portion of its travel from end to end of the track. Surrounding the shaft 6 is a tube 65 or pipe 19, which has threaded connection at the lower end with a guide or roller arm 20 which loosely surrounds the shaft 6, a set of bearing balls 21 being located between the guide arm 20 and shaft to steady the arm. 70 The upper end of the pipe 19 has threaded connection with a collar 22 secured to a sleeve 24 by cap screws 23. The upper end of the shaft 6 is reduced where it passes through the sleeve 24 and the latter is counterbored above and below to receive ball bearing cones 25, 26. The lower cone 25 is supported upon the shoulder formed by the upper end of the shaft 6 and the upper cone 26 is retained by an adjusting nut 27 on the 75 end of the reduced portion of the shaft. 80

The apparatus herein described is designed to be located within a protecting casting or cabinet, as is the usual custom in devices of this class. The reference numeral 85 28 represents the floor of such a cabinet, the walls of the structure being omitted, since my invention has no positive relation thereto. The said floor 28 is supported in any convenient manner at a suitable height above 90 the building floor 11 and is provided with a rectangular opening 29 beneath which the track and carriage are located, so that the column 5 will project therethrough. Suitably supported within the said opening 29 is 95 a guide plate 30 having a longitudinal slot 31 through which the main shaft 6 projects. The roller arm 20 projects at equal distances upon opposite sides of the column and is provided at each end with a pair of anti-friction rollers 32, arranged upon the under side of the said arm, and adapted to engage the outer side of guide ribs 33 cast upon the upper side of the guide plate 30. These ribs are parallel opposite one end of the median slot 31 and the remaining portions are slightly curved and inclined toward the median line as indicated at 34 in Fig. 2. Arranged on the plate 30 and surrounding the other end of the slot 31 is a guide ring 35, of 100 105 110

similar height to the ribs 33 and adapted to be engaged by the rollers 32, when the carriage and column are at this end of the track, the said ring having an opening on 5 one side corresponding with the slot 31 to permit the shaft to pass to the center of the ring.

Radiating from the sleeve 24 are arms 36, the sleeve and arms constituting a spider, which supports parallel rods 37, adapted to 10 have the articles to be displayed hung thereon. Mounted at any desired point on the column 5 is a sleeve 38 having radiating arms 36^a to form a spider similar to the one mounted above and having like rods 37^a 15 fixed on the extremities. This spider is supported upon a collar 39 adjustably secured to the tube 19 by a set screw 39^a, so that the spider may be fixed at various heights on the pipe 19, as indicated in the dotted lines in 20 Fig. 1. The spider when adjusted is locked upon the tube by means of set screws 38^a so as to revolve therewith.

It will be observed that the tube 19 and attached spiders are adapted to be rotated 25 about the central shaft or axis 6, the weight of the revoluble portion being supported upon the ball bearings located in the sleeve 24 of the upper spider, while the balls 21 support the lateral thrust of the guide arm 30 against the said shaft. The hanger rods 37, 37^a extend considerably beyond the spider arms in opposite directions, and the cabinet is made of sufficient width to accommodate these comparatively long fixtures. To construct 35 these cases or cabinets of sufficient depth to permit the revoluble part to be rotated, however, would be undesirable, because of the excessive space which would be required. When the carriage and column 40 mounted thereon are moved forward along the track until the post or shaft 6 reaches the end of the slot 31 and occupies the center of the guide ring 35, the tube 19 and attached spiders may be revolved in either direction as desired, the rollers 32 keeping 45 the column central by engaging the outer face of the ring 35. To replace the apparatus in its initial position it is only necessary to push the fixture rearwardly along 50 its track, and during this movement the rollers 32, coming in contact with the curved or inclined portions of the ribs 33 will turn the arm 20 so as to bring the revoluble portion to its original position by the time the 55 carriage has reached the end of its travel.

It is to be understood that this machine can be used with a single spider if desired when long garments are to be displayed.

Having thus described my invention what 60 I claim as new, is:—

1. A display fixture comprising a carriage, a track therefor, a slotted guide plate arranged above said track, a column mounted on said carriage and extending through 65 said slot, a garment supporting device rev-

olubly mounted on said column, guide arms supported on the column, and ribs on said guide plate adapted to be engaged by said guide arms.

2. A display fixture comprising a carriage, a track therefor, a column comprising a shaft mounted on said carriage, a guide plate arranged above said track, a slot in said plate engaged by said shaft, guide ribs on said plate, a guide ring arranged concentric with one end of said slot, and a guide arm revolubly mounted on said shaft and adapted to engage said guide ribs and ring. 70 75

3. In a display fixture, a carriage composed of an upper and a lower plate adjustably connected, a track on which said carriage is mounted, anti-frictional means between said track and the plates of said carriage, a vertical shaft supported by said carriage, a column rotatable on said shaft, 80 garment supporting means connected with said column, guide means secured to said column, a track arranged above said carriage and having parallel portions and converging portions adapted to prevent the rotation of said guide means, and a circular track arranged in the same plane with the first named track, said circular track adapted to 85 permit the rotation of said guide means. 90

4. A display fixture comprising a carriage, a track therefor, a guide plate arranged above said track, a longitudinal slot in said plate, guide ribs on said plate, a shaft mounted on said carriage and projecting through said slot, a tube revolubly mounted on said shaft, display devices adjustable on said tube, and guide arms fixed on said tube and adapted to engage said 95 100 guide ribs.

5. A display fixture comprising a carriage, a track therefor, a guide plate arranged above said track, a longitudinal slot in said plate, guide ribs arranged on said plate opposite one end of the said slot, a guide ring on the plate concentric with the other end of the slot, a shaft mounted on 105 said carriage and projecting through said slot, a tube revolubly mounted on said shaft, and a cross arm on said tube adapted to engage said guide ribs and ring. 110

6. In a display fixture, a supporting track, a carriage movably mounted on said track, a rotatable column connected with said carriage, guide means arranged on, rotatable with and adapted to support said column, rollers carried by said guide means, a guide track adapted to be engaged by said rollers, and to prevent the rotation of said guide means, and a second guide-track adapted to be engaged by said rollers and to permit 115 the rotation of said guide means. 120

7. In a display device, the combination of a case or compartment, a rotatable rack movable to and from a position within the case, guide ribs connected to the case or compartment. 130

ment and having end portions converging toward the front of the case or compartment, and means connected to the rack for rotative movement therewith to engage the converging portions of said guide ribs as the rack is moved into the case to bring the rack into parallelism with the case or compartment.

8. In a display device, the combination of
10 a case or compartment, a rotatable rack movable to and from a position within the case, a pair of guide ribs connected to the case or compartment and having end portions converging toward the front of the case,
15 and a contacting member carried by the rack to engage one or the other of said guide ribs to prevent contact of the rack with the case as it is bodily moved to and from its position at the front of the case.
20 9. In a display device, the combination of

a case or compartment, a rotatable rack movable to and from a position within the case, a guiding rib device connected to the case or compartment and having separated but converging end portions, a member connected to the rack and normally out of engaging relation with said rib device when the rack is in front position and adapted to be brought into engagement therewith and to embrace said rib device to turn the rack 25 into parallelism with the case or compartment as the rack is moved to its inner position.

In testimony whereof I affix my signature in the presence of two witnesses.

ALFRED GUSTAFSON.
